UNITED STATES PATENT OFFICE.

CHARLES EDWARD RIEDEL, OF DETROIT, MICHIGAN, ASSIGNOR TO DETROIT SCALE MANUFACTURING COMPANY, OF DETROIT, MICHIGAN, A CORPORATION OF MICHIGAN.

LOOP-BEARING FOR SCALES.

1,147,751.

Specification of Letters Patent. Patented July 27, 1915.

Application filed December 19, 1914. Serial No. 878,040.

To all whom it may concern:

Be it known that I, CHARLES EDWARD RIEDEL, citizen of the United States, residing at Detroit, county of Wayne, State of Michigan, have invented a certain new and useful Improvement in Loop-Bearings for Scales, and declare the following to be a full, clear, and exact description of the same, such as will enable others skilled in the art 10 to which it pertains to make and use the same, reference being had to the accompanying drawings, which form a part of this specification.

My invention relates to a loop bearing for 15 scales and is particularly designed for suspending a counterpoise weight from a scale beam. In devices of this character it is customary to provide the loop with a hardened member to receive the knife edge pivot of a 20 scale mechanism and to this end one well known bearing is constructed of highly tempered sheet metal of segmental form lodged in suitable openings in the loop provided for its reception. The segmental member how- 25 ever is frequently broken in assembling it with the loop, it being necessary to contract its diameter that it may enter the eyes of the latter.

One of the objects of the present invention 30 is to provide a loop hanger with a hardened sheet metal member adapted to receive the knife edge pivots of a scale mechanism, the construction being such that the parts may be readily assembled without the necessity 35 of contracting the bearing member in order that it may be engaged with the hanger.

Other advantages and improvements will hereafter appear.

In the drawings accompanying this specification:—Figure 1, is a perspective view of the loop hanger. Fig. 2, is a side elevation of the loop hanger showing the tines of its bifurcated portion spread apart to receive the hardened sheet metal bearing;—the 45 bearing being indicated in section.

Referring now to the letters of reference placed upon the drawings:—A, denotes a hanger having spaced parallel arms A', A', respectively bifurcated and with inwardly

directed tines a, a, forming trunnions adapted to engage a sheet metal bearing B. The walls b,—b, of the bearing are inclined toward each other at the top to form a ridge b', adapted to receive the knife edge pivot of a scale mechanism (not shown) and with 55 depending parallel portions perforated to receive the trunnions a,—a, of the hanger.

Having indicated the several parts by reference letters the manner of assembling the same will be readily understood:—The tines 60 a,—a, of the hanger are initially spread apart to receive the bearing B, between them;—they are then bent toward each other that the ends of the tines may enter the apertures provided in the walls of the bearing 65 for their reception. It will be obvious that the bearing may thus be connected with the hanger without altering its form and without danger of breaking, while a rocking connection is provided between the 70 hanger and the bearing whereby it may readily adapt itself to the coördinate parts of the scale mechanism.

Having thus described my invention what I claim is:—

1. In a device of the character described, a bifurcated member, each of its furcations having tines adapted to be bent to enter apertures in a pivot bearing to serve as trunnions, and a pivot bearing comprising 80 two members spaced apart provided with apertures to receive the tines of each furcation of the bifurcated member, whereby the respective members of the pivot bearing may be held in alinement and linked to the bifurcated member.

2. A device of the character described, comprising a bifurcated hanger the furcations of which have tines directed toward each other adapted to be bent to loosely engage a perforated bearing, and said bearing having inclined wall portions forming a ridge adapted to receive a knife edge pivot and with parallel wall portions spaced apart having apertures to receive the tines of the 95 hanger, whereby the bearing may be loosely linked with the hanger.

3. In a device of the character described,

a pivot bearing having apertures to receive the trunnions of a supporting hanger, and a V-shaped hanger having bifurcated walls, the furcations of which form trunnions 5 adapted to enter the apertures of the pivot bearing, whereby the bearing and hanger are linked together.

In testimony whereof, I sign this specification in the presence of two witnesses.

C. EDWARD RIEDEL.
